UNITED STATES PATENT OFFICE

172,354

DRIER UNIT

Richard A. Line, Marinette, Wis., assignor to
Ansul Chemical Company, Marinette, Wis., a
corporation of Wisconsin

Application May 18, 1953, Serial No. 25,043

Term of patent 14 years

(Cl. D62—2)

To all whom it may concern:

Be it known that I, Richard A. Line, a citizen of the United States, residing at 339 Jefferson Street, Marinette, Wisconsin, have invented a new, original, and ornamental Design for a Drier Unit, of which the following is a specification, reference being had to the accompanying drawing, forming a part thereof, in which:

Figure 1 is a front elevational view of a drier unit, showing my new design; and

Figure 2 is a plan view thereof.

I claim:

The ornamental design for a drier unit, as shown.
